UNITED STATES PATENT OFFICE.

NICHOLAS ACCISANO, OF NEWARK, NEW JERSEY.

CLIPPER.

1,086,799.

Specification of Letters Patent.

Patented Feb. 10, 1914.

Application filed December 14, 1912. Serial No. 736,739.

To all whom it may concern:

Be it known that I, NICHOLAS ACCISANO, a subject of the King of Italy, and residing in the city of Newark, county of Essex, and 5 State of New Jersey, have invented certain new and useful Improvements in Clippers, of which the following is a specification.

In clippers of the type to which my invention appertains, a multiple toothed stationary blade is provided over which the multiple toothed reciprocating blade is operated, the multiple teeth of the two blades serving as a shearing device for shearing the hair from the head of a person 10 or the body of an animal, the hair passing between the multiple teeth in somewhat the same manner as it does between the teeth of a comb. This operation, however, is well known. In using this device where it is desired to grade the clipping, that is, to cut the hair close to the skin at one point and grade the cutting thereof, to gradually lengthen it at others it is necessary to tilt the handles of the clipper using the heel of 15 the stationary blade as a sort of a fulcrum to bear upon the skin of the subject. This often produces uneven cutting and results in the ragged appearance of the hair after the operation is completed.

30 The object of my invention is to provide a clipper with power operating mechanism for reciprocating the movable blade and provide the stationary blade with a pivoted comb on its under side and utilize the movable handle of the clipper for oscillating the pivot comb toward and away from the under side of the stationary blade. The points of the teeth of the comb in operation bear upon the skin or scalp of the subject 35 and as the comb is oscillated away from the stationary blade it serves to elevate the entire clipper from the skin or scalp of the subject. I also provide upon the handles of the device a scale by which the degree of 40 oscillation of the comb may be readily observed, this and other improvements in the clipper forms the subject matter of my invention.

In the accompanying drawings which 45 form part of the specification: Figure 1 illustrates a plan view of my improved clipper with the inclosing cap or cover removed to show the interior mechanism. Fig. 2 is a side elevation partly in section of the clipper. Fig. 3 is a plan view of the stationary blade. Fig. 4 is a plan view of the comb. Fig. 5 is a side elevation of the comb. Fig.

6 is a side elevation of the cap or cover and Fig. 7 is a plan view of the same. Fig. 8 illustrates a slight modification of the driving mechanism for operating the reciprocating blade.

Similar reference numerals refer to like parts throughout the specification and drawings.

65 The clipper consists essentially of a spring barrel 1, having integrally connected therewith the handle 2 and a forwardly extending step 3. The so-called stationary blade 4 is secured to the step 3 by means of two screws 5. This stationary blade is provided with the plurality of cutting teeth 6, at its forward edge. Two upwardly extending posts 7 are rigidly secured to the upper side of the stationary blade 4, which serve as 70 guides for the reciprocating blade 8. The latter blade is provided with the plurality of cutting teeth 9 usually two or three fewer in number than those upon the stationary blade 4. The slots 10 are provided in the 75 reciprocating blade which take over the posts 7 above referred to. The reciprocating blade 8 is also provided with the oval slot 11, in its center for a purpose herein-after to be described. The step 3 is provided with an upwardly extending screw threaded post 12 which serves the double purpose of forming a pivot for the handle 13 and also fastening means of the cover or cap 14. This cap is of the general shape 80 and contour as illustrated in Fig. 7 and is provided with an aperture 15 which takes over the threaded post 12 and is secured to said post by means of the thumb nut 16. The rear end of the cap bearing rests upon 85 the spring barrel 1 as shown while the forward edge rests upon the upwardly extending posts 7. Small dowel holes are provided in said posts 7 to receive the dowel points 17 in the lower side of the cap, so that when 90 in position the thumb nut 16 rigidly secures the cap in position. The rear corners of the stationary blade 4 are notched out as at 18 and in the parallel faces of such notched out portions, I provide the screw holes 19. 95 Within the spring barrel 1 is a coil spring 20, one end of which bears upon the adjusting screw cup 21, and the opposite end bears upon a spring cap 22, the outer face of 100 which is provided with a conical cavity 23. The cap 22 is held from escape by means of the ledge extending around the cavity of the spring barrel 1. The pivot handle 31 as above described is pivotally mounted upon 105 110

the post 12, underneath the cap or cover 14, which serves to retain it in position. This handle is provided with a small ball pointed pin which bears in the conical cavity 23. 5 It will be seen that when the handle 13 is gripped in the hand with the handle 2, the spring 20 serves to yieldingly resist any pressure upon the handle. Projecting laterally from the side of the handle 13, is an 10 arm 24, which normally lies parallel to the side of the spring barrel, said spring barrel serving as a stop for said arm to prevent the spring within the barrel from opening the handle too wide. 15 Upon the parallel faces of the notched rear portion 18 of the stationary blade 4 are pivoted two upwardly extending pivot lugs 25 of the comb 26, said comb normally lying flat against the lower side of the stationary 20 blade, but capable of swinging upon the pivot screws 25; which latter are screwed into the apertures 19. The left hand pivot lug 25 is provided with an upwardly extending supplemental lug 27, which is 25 located just forward of and in position of engagement with the extremity of the arm 25, so that as the arm 24 is moved forwardly by the operation of the handle 13, the comb may be oscillated upon its pivots. Secured 30 to the center of the rear edge of the comb is a flat spring 28, the free end of which bears upon the lower side of the spring barrel 1 and serves to yieldingly hold the said comb flat against the under side of the stationary 35 blade.

In the cap or cover 14 is the journal bearing 29, in which is located the short section of shaft 30, upon the inner end of which is located an eccentric cam 31, the latter when 40 in position being located in the slot 11 in the reciprocating blade. The outer end of the shaft is rigidly secured to a flexible shaft 32 leading from some motor, preferably an electric motor. It will be readily seen that 45 the rotation of the flexible shaft will rotate the short shaft in its bearing and with it the eccentric cam, resulting in the rapid reciprocation of the blade 10. When the handle 13 is moved upon the pivoting post 12, the 50 arm 24 will oscillate the comb away from the blade 4. If the points of the teeth of the comb bear upon the skin or scalp of the subject the result will be the elevation of the 55 stationary blade 4; in fact the whole device will be carried away from the skin or scalp of the subject. The points of the teeth 26' of the comb are curved and normally located in the slots between the teeth of the stationary blade, so that the points of the teeth in 60 the stationary blade may be operated as close to the skin of the subject as possible.

Ordinarily the points of the teeth of the stationary blade are chamfered upwardly as shown in Fig. 2, as this permits the points 65 of the teeth to lie closer to the skin of the

subject and thus clip the hair much more closely than otherwise could be done if the teeth were chamfered or beveled downwardly.

Projecting rearwardly from the spring 70 barrel and extending in the arc of the circle of which the post 12 is the center is a flat scale 33, and upon the handle 13 is located an arm 34, at the outer extremity of which is a pointer 35, in position of register with 75 the divisions upon the scale. The scale and pointer serves as an index to the degree of oscillation of the comb.

While I have shown a specific means of 80 oscillating the comb from the pivot handle 13, I do not desire to confine myself to that only, as any means for oscillating the comb would come within the spirit and scope of my invention.

In Fig. 8 I have illustrated a slight modification of the means for reciprocating the blade 8. In this case the cam slot 36 is provided with the arc shaped ends 37. On the lower end of the short section of the shaft 30, I provide a cam arm 38 which projects 90 into the slot 32 for engagement with the cams 33. It will be readily seen that the rotation of the shaft 30 with the cam arm 34, will result in rapid intermittent reciprocation of the blade 8, and that during the 95 period when the end of the cam arm 34 is not in contact with the cams 33, the blade 8 will be substantially at rest in either one of its extreme positions. These periods of rest are quite essential to the proper operation 100 of the clipper, for the reason that if the shaft 30 is rotated at a high rate of speed, the form of the eccentric cam illustrated in Fig. 1, will leave no short periods of rest for the blade 8, with the result that the hair of 105 the subject will have no time to be arranged properly between the teeth of the stationary blade 4. Ordinarily, however, the shaft 30 does not revolve at the speed which will preclude the eccentric cam 31 from actuating the blade 8 to effectually clip the hair of the subject. Other means may be provided for applying power to reciprocate the blade 8 and I do not limit myself in this respect 110 to any specific means for operating said 115 blade 8.

I claim:

1. In a clipper, the combination of a stationary blade, a handle for supporting said stationary blade, a reciprocating blade, means for operating said reciprocating blade, a comb pivotally mounted upon said stationary blade, a second handle pivotally connected with said named handle and means connecting said second handle with 120 said comb for moving said comb upon its pivot.

2. In a clipper, the combination of a stationary toothed blade, a second toothed blade mounted upon said stationary blade, means 125

- for reciprocating said second blade, a comb pivoted to the heel of said stationary blade, a pair of handles, one of which is rigidly connected to said stationary blade, and the other of which is pivotally connected to the first named handle and a connection between said pivoted handle and said comb for oscillating the latter upon its pivot.
3. In a hair clipper the combination of a pair of relatively movable toothed blades, a supporting handle for one of said blades, a pivoted handle connected to said supporting handle, a comb pivotally mounted in connection with said supporting handle and arm extending from said pivoted handle to a part of said comb for oscillating the latter upon its pivot.
4. In a hair clipper, a toothed blade, a comb pivoted to said blade and having the points of its teeth normally located between the teeth of said blade, and means for oscillating said comb upon its pivot toward and away from said blade.
5. In a hair clipper, a pair of handles, one of which is pivotally connected with the other, a spring for normally separating said handles, a pair of toothed blades, a comb pivotally connected to one of said blades, and a connection between said pivoted handle and said comb for oscillating the latter upon its pivot.
6. In a hair clipper, a pair of handles one of which is pivotally connected with the other, a blade secured to one of said handles, a comb pivotally mounted upon the back of said blade, a spring for normally holding said comb against the back of said blade, a cutting blade mounted upon said first named blade for coöperation therewith, and a connection between said pivoted handle and said comb for oscillating the latter upon its pivot.
7. In a hair clipper, the combination of a supporting handle, an operating handle pivotally connected to said supporting handle, a spring for separating said handles, a toothed blade rigidly secured to said supporting handle, a reciprocating blade mounted upon said first named blade, a comb pivotally mounted upon the back of said first named blade, means connecting said operating handle and said comb for swinging the same away from said first named blade, and a spring for reversing the swing of said comb.
8. In a clipper, the combination of a stationary blade, a handle for supporting said stationary blade, a reciprocating blade, means for operating said reciprocating blade, a comb pivotally mounted upon said stationary blade, a second handle pivotally connected with said first named handle, means connecting said second handle with said comb for moving said comb upon its pivot, and a scale and pointer upon said handles for measuring the degree of oscillation of said comb.
9. In a clipper, the combination of a stationary toothed blade, a second toothed blade mounted upon said stationary blade, means for reciprocating said second blade, a comb pivoted to the heel of said stationary blade, a pair of handles, one of which is rigidly connected to said stationary blade, and the other of which is pivotally connected to the first named handle, a connection between said pivoted handle and said comb for oscillating the latter upon its pivot, and a scale and pointer upon said handles for measuring the degree of oscillation of said comb.
10. In a hair clipper the combination of a pair of relatively movable toothed blades, a supporting handle for one of said blades, a pivoted handle connected to said supporting handle, a comb pivotally mounted in connection with said supporting handle, arm extending from said pivoted handle to a part of said comb for oscillating the latter upon its pivot, a scale upon said supporting handle and a pointer upon said pivoted handle for measuring the degree of oscillation of said comb.
11. In a hair clipper, a toothed blade, a comb pivoted to said blade and having the points of its teeth normally located between the teeth of said blade, means for oscillating said comb upon its pivot toward and away from said blade, and means for measuring the degree of such oscillation.
12. In a hair clipper, a pair of handles, one of which is pivotally connected with the other, a spring for normally separating said handles, a toothed blade, a comb pivotally connected to said blade, a connection between said pivoted handle and said comb for oscillating the latter upon its pivot, and a scale and pointer connected respectively to said handles for measuring the degree of such oscillation.
13. In a hair clipper, a pair of handles one of which is pivotally connected with the other, a blade secured to one of said handles, a comb pivotally mounted upon the back of said blade, a spring for normally holding said comb against the back of said blade, a connection between said pivoted handle and said comb for oscillating the latter upon its pivot, and a scale and pointer connected respectively to said handles for measuring the degree of such oscillation.
- In testimony whereof, I have hereunto set my hand.
- NICHOLAS ACCISANO.
- In presence of—
- LOUIS M. SANDERS
ROSA SCULLY.
